US0D1031674S

(12) **United States Design Patent** (10) **Patent No.:** **US D1,031,674 S**
(45) **Date of Patent:** **** Jun. 18, 2024**

(54) **REMOTE CONTROL DEVICE FOR
INDUSTRIAL EQUIPMENT**

(71) Applicant: **AUTONICS CORPORATION**, Busan
(KR)

(72) Inventors: **Sunkyoung Song**, Busan (KR);
Donghwan Kim, Busan (KR); **Jaeyeon
Kim**, Busan (KR)

(73) Assignee: **AUTONICS CORPORATION**, Busan
(KR)

(**) Term: **15 Years**

(21) Appl. No.: **35/517,628**

(22) Filed: **Jun. 27, 2022**

(80) **Hague Agreement Data**

Int. Filing Date: **Jun. 27, 2022**

Int. Reg. No.: **DM/223610**

Int. Reg. Date: **Jun. 27, 2022**

Int. Reg. Pub. Date: **Jun. 30, 2023**

Kevin L. Soules

(57) **CLAIM**

The ornamental design for a remote control device for industrial equipment, as shown and described.

DESCRIPTION

1. Remote control device for industrial equipment

1.1 : Perspective

1.2 : Rear perspective view

1.3 : Front

1.4 : Back

1.5 : Left

1.6 : Right

1.7 : Top

1.8 : Bottom

The subject design is for the operator to manually operate and control the operation of industrial equipment when repairing industrial equipment such as industrial robots.

1 Claim, 8 Drawing Sheets
